CLAIM

The ornamental design for a golf tee, as shown and described.

DESCRIPTION

FIG. 1 is a perspective view of a golf tee in accordance with our design;

FIG. 2 is a front elevation view of the golf tee in accordance with our design;

FIG. 3 is a back elevation view of the golf tee in accordance with our design;

FIG. 4 is a right side elevational view of the golf tee in accordance with our design;

FIG. 5 is a left side elevational view of the golf tee in accordance with our design;

FIG. 6 is a top view of the golf tee in accordance with our design; and,

FIG. 7 is a bottom view of the golf tee in accordance with our design.

The dashed lines shown in the figures depict portions of the golf tee that form no part of the claimed design; the dash-dot-dash lines shown in FIGS. 1-5 define the bounds of the claimed design and form no part of the claimed design.
